STRAIN RELIEF

Harold Roy Gordon, Flossmoor, and Francis F. Florsheim, Chicago, Ill., assignors to Diamond Wire & Cable Co., Chicago Heights, Ill., a corporation of Illinois

Application October 6, 1939, Serial No. 298,254

3 Claims. (Cl. 173—322)

This invention relates to an improved strain relief and has, for one of its principal objects, the provision of means whereby undue strains and pulls on electrical conductors such as insulated wires will be automatically taken care of and undesirable results from such pulls and strains eliminated.

One of the principal objects of this invention is to provide a simple and economical, yet efficient device, for the relief and elimination of undue strains and pulls on wires and similar structures such as cords, ropes or any related elements.

A further object of the invention resides in the production of a strain relief device which can be readily manufactured in commercial quantities at relatively low prices and which can be assembled with the wire and related structures with a minimum expenditure of time and labor.

20 A still further object of the invention is to provide a strain relief for electrical conductors which will meet the requirements of all the underwriters laboratories and comprise a safe and foolproof installation.

25 Other and further important objects of the invention will be apparent from the disclosures in the accompanying drawing and following specification.

The invention, in a preferred form, is shown 30 in the drawing and hereinafter more fully described.

In the drawing:

Figure 1 is a top plan view of the improved strain relief device of this invention, showing the 35 same in one piece and before assembly.

Figure 2 illustrates the strain relief of this invention assembled on a wire and ready for installation in some electrical apparatus such as a radio receiver or the like.

40 Figure 3 illustrates a modified form of the invention shown in Figure 1 and wherein the device is produced in two pieces. The opening for the wire is shown as of a slightly different shape.

Figure 4 shows a further modification of the 45 structure of Figure 3.

Figure 5 illustrates the strain relief of this invention assembled against a panel or part of a radio cabinet.

50 Figure 6 illustrates in more detail the assembly of the strain relief of this invention in some sort of electrical appliance such as the ordinary radio receiver or the like.

Figure 7 is a side elevation, illustrating the strain relief of this invention applied to a length 55 of wire for application in almost any desired

relationship to some other part of an electrical apparatus or alternatively for preventing undue pulls on lengths of rope, cord or similar elements.

Figure 8 shows a modified form of the invention.

5

As shown in the drawing:

The reference numeral 10 indicates generally a piece of relatively stiff yet somewhat flexible material which forms the body portion of the improved strain relief of this invention. Ordinary 10 commercial fiber has been found to be quite suitable for this purpose although other materials may be employed with considerable success.

In its preferred form, the improved strain relief comprises a length of fiber, preferably 15 rectangular in shape, as shown in Figure 1 and having a plurality of openings punched or otherwise formed therein, there being four openings for rivets or some other fastening elements, these openings being designated at 12 and being of a 20 size to receive suitable rivets or bolts.

At the middle of the length of fibrous material 10 is provided a scored line as shown at 14 whereby the length of material 10 may be bent and doubled upon itself, preferably without breaking. 25

There is likewise provided in the length of material 10 two openings 16 which are for the passage of the insulated wire or other length of material therethrough.

It will be noted that when the plate 10 is 30 doubled upon itself, the openings 16 are offset with relation to each other as best shown in Figure 2, and the wire 18 or other material to be held against undue pulls or strains is passed through one of the openings 16, thence between 35 the two adjacent parts 10 of the strain relief as itself and finally out the other opening 16 as more clearly indicated in Figures 5 and 7.

The two adjacent plate portions 10 could then be fastened together by rivets or the like 20 which 40 pass through the aligned openings 12, and the wire is accordingly held in securely gripped position between the plate elements 10 and without any possibility of its being pulled out of place or even being turned by twisting action. Ob-

viously, when this strain relief element 10 with the associated wire is either placed against or pulled against some relatively fixed element, any further pull on the wire is immediately transmitted through the strain relief to the fixed element, and damage to the wire or electrical connections is avoided. In the case of ropes, cords, strings and the like, this same action occurs.

In Figures 3 and 4, modifications of the invention are illustrated in which single plates 30 55

and 32 respectively are provided, the plate 30 being adapted for association with a similar plate having a circular opening 34 therein, and the same strain relief action takes place by riveting or bolting the two associated plates together by passing such rivets or bolts through the openings 36 provided for this purpose.

In Figure 4, a pair of square openings 38 is shown, and this structure acts in the same manner in that openings of various sizes and shapes can be used, depending somewhat upon the size, shape and consistency of the wires, cords, conductors or elements to be used with the particular strain relief.

15 In Figure 5, a pair of plates such as those shown at 30 in Figure 3 are illustrated as sustaining a wire 18 in strain relief position against one face of a board or panel 40 which may comprise a portion of some electrical equipment such as a radio receiving cabinet or the like. The wire 18 is passed through one opening in the first plate 30 and thence brought across and through the other opening in the adjacent similar plate and finally out to an opening 42 in the plate or panel 40. In this case, bolts 44 can be provided which pass through the openings in the plates 30 and thence through further openings in the panel board or support 40 and are finally fastened in place by means of nuts 46 which are pulled down 25 sufficiently to provide a suitably gripping action on the wire 18. Obviously, screws may be used instead of bolts, or some other fastening means may be employed.

A clearer view of such a structure is illustrated 30 in Figure 6 wherein the panel board 40 is reproduced as also the strain relief plates 30 and the related wire 18 with its terminals fastened to binding posts or the like 50, and this illustration shows more clearly the safety action of the 40 strain relief of this invention in that there is practically no possibility of the ends of the wire 18 being pulled away from the respective binding posts which would, of course, put the particular apparatus out of commission and, perhaps, cause 45 an accident. Furthermore, in the use of this construction, undue twisting action on the wire is prevented, particularly at any portion of the wire beyond the strain relief.

In Figure 8, the rope or wire is shown mounted 50 in a single plate 60 having a plurality of openings 62 therein, preferably three or more, and the rope or wire is threaded through these openings as shown in a manner to produce a snubbing or strain relief arrangement.

It will be evident that herein is provided a very simple yet quite efficient strain relief for electrical conductors, ropes, cords and the like, and which can be readily applied and will practically never get out of order or lose its efficiency even under the most adverse conditions of use or abuse. It will further be obvious that the invention may be applied in other fields without any particular changes in structure except, perhaps, relative dimensions and that the device can be 10 made and used in one or two parts with equal satisfaction.

Also, it will be evident that in the constructions shown in Figures 3 and 4, a single set of dies or punches may be used to produce the 15 plate elements 30 and 32 respectively, and that, in assembling these plates on wires or cords, all that is necessary is to reverse one plate so that the gripping openings will assume the desired staggered relationship.

We are aware that many changes may be made and numerous details of construction varied throughout a wide range without departing from the principles of this invention, and we, therefore, do not purpose limiting the patent granted 25 hereon otherwise than as necessitated by the prior art.

We claim as our invention:

1. A strain relief, comprising a fibrous plate transversely scored adjacent its middle for ready 30 bending, the plate having a pair of similar openings therein, said openings arranged for offset relationship when the plate is bent and doubled upon itself.

2. A strain relief, comprising a fibrous plate 35 transversely scored adjacent its middle for ready bending, the plate having a pair of similar openings therein, said openings arranged for offset relationship when the plate is bent and doubled upon itself and provided for the retentive reception of an electrical conductor.

3. In combination, a conductor and a strain relief therefor, comprising a fibrous plate transversely scored adjacent its middle for ready bending, the plate having a pair of similar 45 openings therein, said openings arranged for offset relationship when the plate is bent and doubled upon itself and provided for the retentive reception of the conductor when fitted into the plates and through the openings.

FRANCIS F. FLORSHEIM.
